UNITED STATES PATENT OFFICE.

JAMES NOEL STEUART, OF BAYSWATER, LONDON, ENGLAND, ASSIGNOR TO G. BEATON & SON LIMITED, OF HOLLAND PARK, LONDON, ENGLAND.

PERCUSSION-FUSE.

1,299,054.

Specification of Letters Patent.

Patented Apr. 1, 1919.

Application filed September 30, 1918. Serial No. 256,274.

To all whom it may concern:

Be it known that I, JAMES NOEL STEUART, a subject of the King of Great Britain, residing at 25 Pembridge Crescent, Bayswater, 5 in the county of London, England, have invented certain new and useful Improvements in or Relating to Percussion-Fuses, of which the following is a specification.

This invention relates to percussion fuses 10 which are particularly applicable for use with rifle grenades, hand grenades or shells.

According to this invention the firing pin or striker of the fuse is so constructed and arranged that it is free to perform a limited movement in the direction of the detonator on shock of discharge (or in the case of hand grenade by a blow of the hand) and to be returned by the reaction of a spring which moves the striker to its original position, this to and fro movement having the effect of liberating a safety device which in falling away renders the striker free to perform its full firing stroke on impact with an object.

25 In order that the invention may be clearly understood and readily carried into effect the same will now be more fully described with the aid of the accompanying drawing, in which:—

30 Figure 1 is a section of a grenade embodying the invention.

Fig. 2 is an exterior view.

Figs. 3 and 4 are plan and elevation respectively of a detail.

35 *a* is the body of the grenade, *b* the detonator holder and *c* the firing pin or striker.

In the embodiment shown the safety device comprises a ring or collar *d* of such a character as to permit of its being sheared 40 into segments on shock of discharge (or by a blow of the hand in the case of a hand grenade) said collar *d* being fitted loosely between the head *c'* of the striker and the end of the chamber or casing *e* within which

45 the striker *c* operates against the action of the spring *f*. The portions or segments of the ring or collar which are to be separated or sheared are connected by thin webs *d'* capable of being fractured or severed by 50 means of a shearing blade *c''* in or on the head *c'* of the striker *c*, the arrangement being such that the head of the striker will bind or hold the severed parts of the ring or collar *d* against the end of the casing *e* until

55 the spring *f* reacts to return the striker to

its normal position. Thus, the collar *d* may consist of a ring, see Figs. 3 and 4, slotted at *d''* and reduced or formed with flats at *d'''* to afford the thin connecting webs *d'*. In lieu of the webs *d'* or their equivalent the segments may be held together by wire or other appropriate means capable of being readily sheared or cut to free the segments on shock of discharge. The striker *c* is prevented from coming into contact with the detonator on its initial movement, while as the head *c'* of the striker returns to its normal position, and thus releases the severed segments, the latter will fall away and permit the striker *c* to make its full stroke 70 and fire the detonator of the fuse *b* on impact with an object. The head *c'* of the striker may be recessed at *c''* to assist in retaining the segments between the head of the striker and the end of the casing after 75 shearing, and thereby provide a safety device which prevents the striker *c* moving a sufficient distance to come into contact with the detonator under shock of discharge.

The usual safety pin *g* for locking the 80 striker *c* may be passed through slots or openings in the casing *e* and an opening *c''* in the striker *c*.

What I claim and desire to secure by Letters Patent of the United States is:—

1. A percussion fuse for grenades or shells comprising a firing pin, means associated with said firing pin which while allowing it to move in the direction of the detonator on shock of discharge prevents said pin from 90 acting on the detonator during such initial forward movement, means for returning the firing pin to its normal position and freeing the pin to enable it to perform its full firing stroke on impact with an object.

2. A percussion fuse for grenades or shells comprising a firing pin, a safety device associated with said pin which while allowing it to move a predetermined distance on shock of discharge prevents said pin coming into 100 contact with the detonator of the fuse, means for returning the firing pin to its initial position to release the safety device to allow the said pin to perform its full firing stroke on impact with an object.

3. A percussion fuse for grenades or shells comprising a striker, means associated with said striker to constitute a safety device for preventing the striker making a full firing stroke on shock of discharge, means for liber- 110

ating said safety device, and means for returning the striker to its normal position to allow the safety device to fall away whereby the striker may on its next forward movement make the full striking stroke.

4. A percussion fuse for grenades or shells comprising a striker, a segmental collar associated with said striker, means for maintaining the collar in position to prevent the 10 striker making a full firing stroke on shock of discharge, and means for releasing said collar during the return movement of the striker to its initial position.

5. A percussion fuse for grenades or shells 15 comprising a firing pin, a segmental collar

associated with said pin, means for holding the segments intact under normal conditions, means for disconnecting said holding means, and means for causing said segments to be released to permit them to fall away from 20 the firing pin.

6. A percussion fuse for grenades or shells comprising a firing pin, a safety device associated with said pin, means for releasing said safety device and holding it in the safety 25 position on shock of discharge, said means serving to permit the said safety device to fall away during flight on the return movement of the pin to its normal position.

JAMES NOEL STEUART.
